United States Patent Office.

EUGENE A. TOUNLEY AND EMIL S. FRIEDRICH, OF WASHINGTON,
DISTRICT OF COLUMBIA.

Letters Patent No. 89,361, dated April 27, 1869.

IMPROVEMENT IN STEAM-PLOWS.

The Schedule referred to in these Letters Patent and making part of the same.

To all whom it may concern:

Be it known that we, EUGENE A. TOUNLEY and EMIL S. FRIEDRICH, of the city and county of Washington, in the District of Columbia, have invented a new and improved Steam-Plow; and we do hereby declare that the following is a full and exact description of the same, reference being had to the accompanying drawings, and to the letters of reference marked thereon.

The invention consists of the means used for propelling or moving the machine to which the plows are attached, either forward or back, or turning the machine around.

It further consists in the construction of the traction-feet and their manner of operation.

It further consists in the devices used by which the machine is caused to diverge from a right line or for turning it around; and

It further consists in the devices whereby the plows are elevated or depressed, as desired, to any depth in the ground or completely clear of the ground.

To enable others skilled in the art to make and use our invention, we will proceed to describe its construction and operation.

Figure 1 is an upright side view of the machine; Figure 2 is a plan view of the same;

Figure 3 is a view of the bottom or under side of the same;

Figure 4 is an upright end view; and

Figure 5 is a view of a plow and standard.

In the drawings—

A represents the frame of the machine in the form represented, and to which the operating-devices are connected.

B B are the two main driving-shafts, placed transversely underneath the platform or frame A, and having bearings firmly fixed to said frame.

C C are wheels; four in number, freely revolving on shafts B.

D D are cams placed eccentrically upon shafts B.

D' D' are cranks upon the same shafts, and do the same office as cams D D, and are placed so that the cranks or cams will not all be coincident in their revolutions, but placed to make the feet or treads act on the ground successively.

E E are frames in which the traction-feet a a are placed, and in which they freely work in the holes a' a'.

F F are caster-wheels for giving direction to the machine.

G G are grooved wheels on upright shafts g g.

H is a transverse shaft, having bearings H', and upon said shaft are segmental toothed pinions, which work into grooved wheels G G, and operate to raise and fall the caster-wheels F F by means of lever H'.

G' is a lever attached to shaft g g by means of a connecting-bar and link, and operates to turn caster-wheels F to give direction to the machine.

I I I are the plows firmly attached to standards I' I', which have teeth i i.

J is an angular transverse shaft attached to frame A, and on which are as many segmental pinions j as there are plows to be operated upon.

These segmental pinions j have teeth which fit into teeth or gear on standard I' of the plows, and operate to raise and lower the plows by means of the lever K, which is firmly fixed upon shaft J, and rotates said shaft and pinions.

k is a detent that holds against the teeth of a ratchet-wheel to keep it and the plows in place.

k' is a pawl upon lever K, with a spring, k'', to hold it in position to catch on the teeth of a ratchet-wheel on shaft J to turn the shaft, and thus raise and lower the plows.

I'' I' are diagonal plates on the top and bottom of frame A, with mortises to receive the standards of the plows and tend to hold the plows firmly in their position, whilst the standards can freely slide through the mortises.

O and O' are rollers upon shafts O''.

S represents a steam-engine, which may be of any suitable construction, and with any arrangement of devices for communicating motion to the driving-shafts B B.

Many attempts have heretofore been made to adapt a locomotive-engine having revolving traction-wheels to the purpose of plowing; but such attempts have failed mainly for the reason that with revolving traction-wheels, it requires the weight of the engine and machine to be enough to overcome the resistance to the plows in order to move forward and successfully do the work, and all this great weight has to be propelled by the power of the engine which makes the machine unwieldy, expensive, and has a want of capacity of adapting itself to the varying surface of the ground, as well as to the texture of the ground itself.

The invention as herein described is intended to overcome the objections heretofore experienced in the want of sufficient traction to surely perform the operation of plowing to the extent of the power of the engine employed.

To do this we substitute for the traction-wheels in common use traction-feet or treads, which alternately come in contact with and take hold of the ground, and when so in contact with the ground, the power is exerted through them in the direction parallel with the plane of motion of the machine and plows, thus producing the greatest effect with a given amount of power upon the plows in propelling them forward, and in a sure and reliable manner without any fear of slipping or stopping, and to this end and purpose we place the frames E E having the traction-feet or treads a, inserted, and working therein, as shown in fig. 1, upon either revolving cranks or cams on shafts B B.

The frames E E have parallel bars, secured in proper position by bolts, any number necessary to give the strength to sustain the strain, and through these bars in holes for that purpose, the stems of the traction-feet or treads pass, any number of which may be used, and around the stems of the feet or treads, and between the bars are placed coiled springs b, the lower ends of which are securely attached to the stem of the treads. These coiled springs may be constructed so as to have a greater or less flexibility, as desired, by different-sized wires in their construction, or there may be a screw-nut placed underneath the upper bar to screw down on the stem and contract the spring so that it will be less flexible.

The traction-feet or treads a may be of metal alone, or they may be shod with wood, or rubber or other substance, and in any desired shape, and the stems, where they pass through the bars of the frame, may be round, square, or of any other form desired. They may be used singly or in pairs, as seen in fig. 3 at a', by using a tread or foot that will connect two or more together.

When the frames E E are thus constructed, they are placed over cams D or cranks D' on shafts B B, in such manner that when the shafts are caused to revolve by engine S, connected in any suitable way by gear or otherwise to give motion to said shafts, as shown in fig. 2, the traction-feet or treads are forced upon and in contact with the ground, and as they come in such contact, they remain firmly in their position until the revolution of the crank or cam raises them from contact with the ground, and are thus the means of propelling the machine forward.

These frames may be eased so as to prevent dust from adhering to the feet, as seen in figs. 2 and 3.

The cams or cranks are placed upon the shafts B B, so that in their revolution, carrying the frames E E and feet a, their greatest eccentricity will be on a perpendicular line through the centre of the shafts at the same time, and so arranged as not to bring all the frames coincident in their actions, but to act at different times and at different points in the revolution of the shafts, or they may be so arranged that two or three frames with their feet will act at the same instant and during a half revolution of the shafts, or so that there will be three or more points in the revolution of the shafts at which they will come into contact with the ground.

Any number of these frames may be used upon the shafts B B, but of course proportioned to the number of plows and weight of the machine.

When the feet or treads are in contact with the ground, the coiled springs b make them flexible, or tend to hold them in firm contact until in the revolution of the crank or cam, they are raised out of such contact; but they are to be graduated so as to have a greater downward projection than just to come to the surface of the ground, as in that case there would be no traction, and the weight of the machine would be upon the plows and rollers, for it is designed that these treads or feet will in ordinary cases sustain nearly all the weight of the machine when in the position given by the cranks or cams while their greatest eccentricity is down or underneath the shaft.

These springs also assist the feet or treads in having a firm hold upon uneven or soft ground, as they are as effectual in operation on such ground as upon the surface that is even, smooth, and hard, which makes their construction and application of the means of propulsion reliable and sure in all conditions and shape of surface of the ground.

The free wheels C C on shafts B B are not calculated to sustain the weight of the machine unless in passing over uneven ground, they may strike some high point, when they will assist in mounting the machine over it.

The plows I I are in the common form, and are firmly attached to standards I I', which standards have cogs or teeth in one edge into which gear cogs or teeth on segmental pinions j on diagonal shaft J, which is parallel with the oblique line of direction of the plows with relation to the frame A.

Firmly fixed to shaft J is lever K. By operating this lever K the shaft J is rotated, and the segmental pinions j cause the raising or falling of the plows, so that by the motion of the lever K the plows are adjusted to any desired depth in the ground, or they can be raised high enough to be entirely free from and above the ground, as in the case of turning the machine around, or in travelling to or from the field.

For giving direction to the machine, and for causing it to turn around when desired, caster-wheels F F, in suitable frames are used, and are attached to upright shafts g g, and to which is attached lever G'.

The two shafts g g are connected so as to be operated upon by lever G' by connecting-bar h and link h', so that by turning the lever G' to the right or left will cause the machine to be deflected from a direct line, or by turning the lever more it will cause it to turn completely around.

The caster-wheels must be made to rise and fall, for they do not want to be in contact with the ground only when it is desirable to turn the machine, or if in contact, they can be forced down to take a greater amount of the weight when desired.

To do this, grooved wheels G G are placed upon shafts g g, and into these grooves work the cogs or teeth of segmental pinions G" G" on shaft H, and to which is fixed lever H", and by depressing lever H" causes shaft H, with the toothed pinions G" G", to press the caster-wheels firmly down upon the ground, or enough so to cause the machine to be turned from a straight line or completely around.

h" is a hook which holds the lever down when desired.

At either end of the machine are rollers O, and extending outside of the frame are the auxiliary rollers O' O', all on shafts O" O"

These rollers are used for levelling hillocks or breaking down weeds or obstacles in the way of the successful operation of the traction-feet, caster-wheels, or the plows.

The plows and the devices for raising them may be, if desired, arranged on a separate frame from that upon which the power is placed, and by being attached by chains or other means, can then be drawn by the machine above described without departing from the principle of our invention.

This arrangement of devices can be made useful for other purposes than plowing, and the power can be used as stationary to drive other machinery by placing upon shaft B bevel-wheel V to gear into pinion w on shaft x, and having crank-wheel y, by simply raising it up so that the traction-feet will not touch the ground, or by taking off the frames E E from shafts B B.

It can also be used without the plows as a locomotive on common roads, street or other railways, and for propelling reaping and mowing-machines; in short, it may be used wherever a locomotive power is required.

We lay no claim to the steam-engine or its connection with the machine, as any well-known means of connecting the power of the engine to our machine may be used.

Having thus described our invention,

What we desire to secure by Letters Patent, is—

1. The frames E E having the traction-feet or treads a a, coiled springs b, constructed in the manner and for the purpose substantially as described.
2. The combination of the shafts B B, cams D, or

cranks D', with the frames E E, constructed and arranged to operate in the manner substantially as described.

3. The combination of the lever G', connecting-bar h, link k', with shafts g g, and caster-wheels F F, arranged to operate substantially in the manner and for the purpose as described.

4. The combination of the lever H" shaft H, segmental pinion G", with grooved wheels G G, shafts g g, and caster-wheels F F, arranged to operate in the manner and for the purpose substantially as described.

5. The combination of the lever K, having pawl k', spring k", with segmental toothed pinion j, shaft J,

and toothed standard I', for the purpose substantially as described.

6. The flexible traction-feet or treads a a, when used for propelling a machine, substantially as described and for the purposes set forth.

7. The steam-plow machine above described, when the several parts are constructed, arranged, and combined together in one machine in the manner substantially as set forth.
